UNITED STATES PATENT OFFICE.

IRVING V. PERINE, OF EAST ORANGE, NEW JERSEY, ASSIGNOR TO THE
CAUSEY & BLANCHARD, OF NEW YORK, N. Y.

DESIGN FOR A BOW-SHIELD.

SPECIFICATION forming part of Design No. 33,622, dated November 27, 1900.

Application filed October 28, 1900. Serial No. 34,508. Term of patent 3½ years.

To all whom it may concern:

Be it known that I, IRVING V. PERINE, a citizen of the United States, residing at East Orange, county of Essex, and State of New Jersey, have invented and produced a new and original Design for Bow-Shields, of which the following is a specification, reference being had to the accompanying drawings, forming a part thereof.

10 Figure 1 is a rear elevation of the bow-shield, showing my design. Fig. 2 is a plan view of the bow-shield, and Fig. 3 is a side or end view thereof.

15 As shown in the drawings, the leading or material features of my design consist of the widened ends or wings 10, which when viewed in elevation are rounding or nearly oval, the reduced middle portion 11, and the open-work structure on the back of the design.

20 The bow-shield is reduced in the middle, as shown at 11, and its opposite ends are widened and rounded or curved to form the two wings 10, which when viewed in plan are curved or bent backward, as in Fig. 2, and

which near the center have through them the 25 circular openings 12. On the center and back of the shield is an open-work structure, which when viewed in plan has a general S shape, with one member 16 lying on the front of the design and with the body portion of the structure on the back, this body portion comprising the members 13, which are bent inward, as shown at 14 in Fig. 1, and merge in the laterally-extending loop 15. The shield is left plain at both sides, except for the openings 30 12 and the open-work structure referred to.

Having described my invention, what I claim as new, and desire to secure by Letters Patent, is—

25 The design for a bow-shield, herein shown 40 and described.

In testimony whereof I have signed my name to this specification in the presence of two subscribing witnesses.

IRVING V. PERINE.
